(74) Attorney, Agent, or Firm — Matthew G. McKinney,
Esq.; Allen, Dyer et al.(57) **CLAIM**

The ornamental design for stun gun electrodes, as shown and described.

DESCRIPTION

FIG. 1 is a front elevational view of the stun gun electrodes; FIG. 2 is a rear elevational view of the stun gun electrodes; FIG. 3 is a left side elevational view of the stun gun electrodes; FIG. 4 is a right side elevational view of the stun gun electrodes; FIG. 5 is a top view of the stun gun electrodes; FIG. 6 is a bottom view of the stun gun electrodes; and, FIG. 7 is a partial top perspective view of the stun gun electrodes. The broken lines in the figure drawings show environmental structure that forms no part of the claimed design.
